JAMES C. DAWSON, OF WEBSTER GROVES, MISSOURI, ASSIGNOR TO ELMA N. DAWSON,
OF WEBSTER GROVES, MISSOURI

LOOSE LEAF BINDER MECHANISM

Application filed May 31, 1930. Serial No. 458,448.

This invention relates to improvements in loose leaf binder mechanism.

The objects of the present invention are to provide means to secure the easier operation of the toggles carrying the paper holding prongs to prevent the deformation of the cover plate which occurs when pressure is applied at the wrong spot and to secure the maximum mechanical advantage from the smallest amount of metal in the booster lever.

With reference to the drawing,

Fig. 1 illustrates a ring binder mechanism as applied to the book cover;

Fig. 2 is a vertical, longitudinal section of the end portion of the device shown in Fig. 1;

Fig. 3 is a vertical, transverse section taken on the line 3—3 of Fig. 2;

Fig. 4 is an end view of the device; and

Fig. 5 is a detail showing of the operating or booster lever.

In my Patent No. 1,662,303 of March 13, 1928, I illustrated a booster lever fulcrumed upon the flanges of the base plate in association with a ring binder system. The curvature of this lever corresponded substantially to the curvature of the cover plate of the binder. The present invention is a substantial improvement over the form there shown in that I assure the fact that the pressure will be applied at the correct position and that it will not be applied to the cover plate to cause deformation and bad appearance of the plate.

With reference to Fig. 3, the ring binder mechanism, generally indicated by 10, comprises a spring backing plate 11 having hook shaped margins 12 and 13 which form pivots for the toggle plates 14 and 15. The toggle plates carry the paper holding prongs 16 and 17. The inner edges of the toggle plates are articulated and retained in position by the double flange studs 18. The operating or booster lever, generally indicated by 19, comprises a booster arm 21, a thumb piece 22, and a connecting arm 23. Slots 24 and 25 cut into the connecting arm 23 allow the engagement of the operating lever with the

hook shaped margins 12 and 13. The V-shaped extension 26 of the spring backing plate 11 is bent at right angles to form a stop and lock for the operating lever.

As indicated at 27, Fig. 2, the cover plate 28 is longitudinally curved at its end bringing the end portion down to the plane of the margin of the spring backing plate, which is also the longitudinal margin of the cover plate. As will be noticed from Figs. 2 and 5, the thumb arm 22 is disposed at a considerable angle away from the horizontal, so that the included angle between the connecting arm 23 and the thumb arm 22 is substantially more than 90°.

When the operator seeks to open the paper holding prongs, he presses upon the thumb arms of the operating levers of either end of the loose leaf holding mechanism. Due to the fact that the cover and the arm together form a transverse notch extending across the apparatus, the thumb is naturally placed in the notch, and pressure when it is applied is applied by a rolling of the thumb out at the extremity of the lever 22. Using the same blank and exactly the same amount of metal as in my previous booster levers, it will be noticed that the effective lever arm causing the opening of the toggles is considerably longer than in designs of levers which extend practically parallel to the cover plate. I am able, therefore, to gain a very considerable mechanical advantage without increasing the amount of metal used. Also, the upwardly extending thumb plate makes a sort of buttress against which the thumb naturally pushes and does not slip as in the prior case. It has been found, too, that operators of loose leaf devices are not particularly careful where they apply pressure and as a result, the cover plate is frequently pressed instead of the thumb lever.

Unless the cover plate is substantially reinforced at its terminals, it will be deformed and the hooked margins separated from the edge of the spring backing plate. The arching of the end of the cover plate for the purpose of forming the thumb guide also materially stiffens the cover plate so

much that any usual amount of pressure which might be placed upon it is borne without deformation of the plate.

What I claim, therefore, is:

1. A loose leaf binder mechanism having a transversely curved cover plate longitudinally curved at its ends, a toggle-operating lever normally positioned at an acute angle to the cover and forming with the longitudinal curve of the cover plate a V-shaped transverse recess serving as a thumb guide.
2. A loose leaf binder mechanism having a spring base member, toggle members pivoted therein, an arched over plate fitted over said base member and having its end portions downwardly inclined, operating levers for the toggles positioned adjacent to said portions, each lever having an upwardly and backwardly inclined thumb piece forming with the adjacent end of the cover plate a recess serving as a thumb guide.
3. In a loose leaf binder, pairs of paper holding prongs, a pair of toggle members carrying said prongs and articulated at adjacent edges to form a toggle adapted to bend upwardly to separate the pairs of prongs and to bend downwardly to bring the prongs together, a backing plate beneath the toggle members and having margins against which the toggle members act, an operating lever adapted to act upon the toggle members and the backing plate simultaneously to open the prongs, said lever comprising a transverse portion fulcrumed adjacent to the margins, a thumb piece projecting upwardly and outwardly from the transverse portion, a lifting arm engaging the toggle members, and an arched cover plate having its end portion inclined upwardly and inwardly from the thumb piece.
4. In a loose leaf binder mechanism having a pair of articulated toggle members carrying paper holding prongs and a supporting plate containing the toggle members, an operating lever of relatively great mechanical advantage for the toggle members comprising an intermediate portion fulcrumed in an end portion of the mechanism, a booster arm extending from the intermediate portion and adapted to engage the toggle members, and a relatively long transversely curved thumb arm extending substantially diagonally from the fulcrum axis of the intermediate portion.

In testimony whereof I affix my signature.

JAMES C. DAWSON.
